DESIGN FOR A BRACELET

Adolph Katz, New York, N. Y., assignor to Cohn & Rosenberger, Inc., New York, N. Y., a corporation of New York

Application January 22, 1942, Serial No. 105,356

Term of patent 3½ years

To all whom it may concern:

Be it known that I, Adolph Katz, a citizen of the United States of America, residing in city of New York, county of New York, and State of New York, have invented a new, original, and ornamental Design for a Bracelet, of which the following is a specification, reference being had to the accompanying drawing, forming part thereof.

Fig. 1 is a plan view of a bracelet showing my new design.

Fig. 2 is an edge view thereof.

I claim:

The ornamental design for a bracelet, substantially as shown.

ADOLPH KATZ.
